UNITED STATES PATENT OFFICE.

HENRY W. PLEISTER, OF WESTFIELD, NEW JERSEY, ASSIGNOR TO HENRY B. NEWHALL.

BOLT-ANCHOR.

1,248,009.

Specification of Letters Patent. Patented Nov. 27, 1917.

Original application filed January 20, 1917, Serial No. 143,423. Divided and this application filed July 17, 1917. Serial No. 181,001.

To all whom it may concern:

Be it known that I, HENRY W. PLEISTER, a citizen of the United States, residing at Westfield, in the county of Union and State 5 of New Jersey, have invented certain new and useful Improvements in Bolt-Anchors, of which the following is a specification, taken in connection with the accompanying drawings. This application is a division of 10 my copending application Ser. No. 143,423.

In my copending application Ser. No. 160,416 I have illustrated, described and claimed a ductile anchor having a body portion which gradually increases in thickness 15 from the outer end to a point intermediate its ends, and from that intermediate point being of substantially uniform thickness to substantially the other end of the anchor it being understood that the expanding screw 20 cuts its own coöperating threads in the anchor.

In that copending application I have also described and claimed such a ductile anchor, as previously described, having inclined and cylindrical bores provided with internal ribs 25 of substantially the same depth or height located on both the said inclined and cylindrical bores.

My invention relates to bolt anchors.

More particularly my present invention relates to that class of bolt anchors known as "anchors", "lead anchors" and "screw anchors", in which the material of the anchor is formed of more or less ductile material 35 such as an alloy of lead, in which a wood screw will cut its own coöperating female threads. Such anchors are used to hold lighter work than are lag shields.

In the present form of anchors the maximum expansion is approximately at the extreme inner end of the anchor. In practice this is often a serious detriment in that the wood screw having forced the anchor out to its maximum expansion binds and it is impossible to bring the head of the wood screw 45 up flush with the work. This requires the hole to be enlarged entailing additional labor and expense, or a different size anchor has to be used.

By my invention I overcome this serious objection and give a longer surface of maximum contact or grip on the exterior of the anchor, thereby giving an increased frictional hold, and distributing this maximum 55 grip over a larger area than with the present

form of anchors. My invention further permits the wood screw to coöperate with the anchor with less effort than with the present forms.

In my present invention I provide the interior of the anchor with longitudinally extending ribs or surfaces which first engage and guide the screw as it is screwed home. The wood screw cuts its own coöperating screw-threads in these ribs or surfaces, and 65 generally, though not necessarily, cuts entirely through the ribs into the body of the anchor.

In my present invention I provide the anchor with a body formed with an axial bore inclined from near one end to a point intermediate the ends of the anchor, and from that point merging into a cylindrical bore, the inclined bore being provided with 70 internal ribs which are preferably of the 75 same height.

My invention further relates to certain details of construction which will be described in the specification and pointed out in the claims.

In the drawings the same reference numerals refer to similar parts in the different figures.

Figure 1 is a longitudinal, vertical section of my present invention;

Fig. 2 is a vertical section of the bolt anchor shown in Fig. 1, located within a wall or other support and coöperating with a wood screw;

Fig. 3 is a transverse vertical section, substantially on the line 3—3 of Fig. 1, looking in the direction of the arrows;

Fig. 4 is a transverse, vertical section, substantially on the line 4—4 of Fig. 1, looking in the direction of the arrows; and

In the illustrative embodiment of my invention, 1, Fig. 1, is an anchor having a collar 2 and tines 3 and 4. This anchor has a body portion 5 provided with an inclined or conical axial bore 6 extending from substantially one end 7 to a point 8, which is the nearest approach to the axis of the anchor, and which is located between the end 7 and the end 9. From the point 8 the axial bore is cylindrical to the end 9 of the anchor. Of course the particular location of the point 8 may be varied. On the inclined or conical axial bore 6, I form longitudinally extending ribs 10 of substantially the same height throughout their length. The inner 105 110

ends of the longitudinally extended ribs 10 merge, at the points 8, 8, into the cylindrical unribbed bore 11 of the anchor.

In my present invention, the point 8, 5 where the ribs 10, 10 approach the nearest to the axis, is due to the formation of the body portion 5 rather than to varying the height or depth of the ribs 10, which is one of the forms shown in my parent application. These ribs 10 serve to guide the entering wood screw 12 and permit its easy passage into the anchor, its male threads 13, cutting their own coöperating female threads in the ribs 10, and usually, though not necessarily, in the body 5 of the anchor also.

It is, of course to be understood, that the depth of the screw threads cut by the screw 12, depends upon the relative size of the anchor, the screw, the size of the hole 14 and 20 the work or load 15. When this anchor is placed in the hole 14 of the support 16 its tines 3 and 4, will be expanded, the maximum grip of the anchor in the hole of the support 16 will extend substantially from 25 the points 17, 17 to the points 18, 18, thus giving a long surface of contact and increased frictional hold and distributing the maximum grip over a larger area than the old form of lead anchor now on the market. 30 These old forms employ a uniformly tapering axial bore in which the maximum grip is at the extreme inner end of the anchor equivalent to the points 18, 18.

Not only is it easier to position the wood 35 screw 12 and to obtain a stronger and more lasting grip upon the wall of the hole 14, but when the support 16 happens to be material which may be damaged, as for example a thin slab of marble or plaster, or any 40 other material, the maximum grip is distributed over a larger area to prevent any damage to the support.

In Fig. 2 I have shown the work 15 of a certain thickness held to the face 19 of the 45 support 16. The same size anchor and wood screw 12 will support different thicknesses of work and permit in all cases, the head 20 of the wood screw 12 to be brought up flush with the work without the screw jamming 50 in the anchor in a position where its head 20 cannot be brought up snugly against the work. That the screw does not jam is due to the fact that the point of maximum expansion is extended over a relatively large 55 surface of the anchor, so that the end 21 of the screw 12 can be brought anywhere along the unribbed or plain cylindrical bore 11, or past the end of the anchor, as may be found

necessary to bring the head 20 flush against the work 15 and at the same time obtain the 60 requisite maximum expansion of the anchor. In the old form, where the maximum expansion is at the end of the anchor, at points equivalent to the points 18, 18, the screw would often jam at this point before its 65 head could be brought flush with the work, 15, whatever its thickness may be, requiring the removal of the anchor and the enlargement of the hole, or the use of a different 70 size anchor.

My anchor may be formed of any exterior configuration. I have shown it provided with longitudinal extending ribs 22, 22, on the collar extending slightly above the transverse ribs 23, 23.

In the different figures of the drawings, for purpose of illustration, I have somewhat exaggerated the preferred angle of the inclined portion of the axial bore.

Having thus described this invention in 80 connection with an illustrative embodiment thereof, to the details of which I do not desire to be limited, what is claimed as new and what is desired to secure by Letters Patent is set forth in the appended claims. 85

1. An article of manufacture comprising a ductile anchor having a body portion of varying thickness from one end to a point intermediate its ends and from that point being of uniform thickness to the other end 90 of the anchor, said anchor being provided with an inclined and cylindrical axial bore and internal ribs mounted only in the inclined axial bore.

2. An article of manufacture comprising 95 a ductile anchor having an internal bore with an inclined ribbed surface reaching its minimum diameter between its ends and merging into a cylindrical unribbed bore.

3. An article of manufacture comprising 100 a ductile anchor having an internal bore with an inclined surface reaching its minimum diameter between its ends and merging into a plain cylindrical bore, and ribs of substantially the same height upon the inclined surface only.

4. An article of manufacture comprising 105 a ductile anchor having an internal bore of different diameters, and ribs upon that portion of the bore of the greatest diameter 110 only.
